C. F. DAUSMANN

WEB PRINTING PRESS

Filed Feb. 10, 1922

UNITED STATES PATENT OFFICE.

CHARLES F. DAUSMANN, OF BROOKLYN, NEW YORK, ASSIGNOR TO THE PRISMATONE CO. INC., OF NEW YORK, N. Y., A CORPORATION OF NEW YORK.

WEB-PRINTING PRESS.

Application filed February 10, 1922. Serial No. 535,607.

To all whom it may concern:

Be it known that I, CHARLES F. DAUSMANN, a citizen of the United States, and a resident of Brooklyn, in the county of Queens and State of New York, have invented a certain new and useful Improvement in Web-Printing Presses, of which the following is a specification.

This invention relates to web printing presses of that type wherein a plurality of spaced printing units or couples are employed, each of the printing units including a printing cylinder and impression roller or the mechanical equivalents thereof.

It is the primary object and purpose of my present invention to provide an improved mounting and arrangement of registering devices between the spaced printing units or couples especially with relation to the movable elements or impression rollers of the printing couples, together with a suitable mechanism whereby all of the impression rollers and the registering devices may be simultaneously withdrawn as a unit from their operative positions with relation to the printing cylinders and the web respectively so that the removal of the web from the press and the insertion of a new web therein may be expeditiously performed.

More particularly, in one practical embodiment of the invention, I propose to mount or support the web registering devices entirely between and upon the bearing castings of the impression rollers of adjacent spaced printing couples. Preferably, I provide means whereby the registering devices may be adjusted relative to said bearings in order to apply a proper tension to the web, to the end that the web will be

maintained in absolutely precise and accurate registration with the printing cylinders as it passes successively from one printing couple to another. The bearing castings for the impression rollers are movably mounted upon the press frame and a manually operable throw-off mechanism is connected to each of these castings. It will, therefore, be apparent that when the throw-off mechanism is actuated, the series of impression rollers with the registering devices mounted upon the bearing castings for said rollers are bodily moved as a single unit either into or out of operative position.

In one embodiment of my invention which I have found highly successful in practise, the

registering devices for the web each consists of means for utilizing the attractive influence of an electrostatic charge for the purpose of holding the web in registering relation with the printing cylinder, and my present invention broadly comprehends the arrangement or association of such electrostatic charge producing devices with the bearing castings for the impression rollers so that the impression rollers may be withdrawn from operative relation to the printing cylinders and the web relieved from the influence of the several electrostatic charges by one and the same operation.

With the above and other objects in view my invention consists in the improved printing press and in the form, construction and relative arrangement of the parts constituting the several novel features thereof as above characterized, all of which will be hereinafter more fully described, illustrated in the accompanying drawing and subsequently incorporated in the subjoined claims.

In the drawing I have illustrated a fragmentary vertical sectional view through a web printing press showing several of the printing units or couples and the web registering devices. It will be understood that I have illustrated only so much of the entire press as is requisite to a clear understanding of my present improvement. To this end there is shown in the drawing one of the side frames or standards 10, the other side frame being removed to reveal the arrangement of the mechanism disposed between said frames.

Between the side frames a series of vertically spaced printing units or couples are arranged, each consisting of a printing cylinder 11 having the ends of its shaft 12 journaled in suitable bearings on the side frames, and an impression roller 13. The shaft 14 of the impression roller is journaled at its ends in suitable bearings on the castings 15 which are pivotally mounted at their lower ends upon a transversely extending rod 16 fixed at its extremities in the side frames 10 of the press.

The printing cylinder is preferably of metal and has an etched intaglio printing surface, while the impression roller which coacts with said cylinder is provided with a rubber cover or sheath. Ink is supplied to the surface of the printing cylinder by

means of the usual inking roller, not shown. Any suitable arrangement of gearing may be provided for driving the printing cylinders, such for instance as that shown in 5 my prior application for patent filed February 28th, 1920, Serial #362,030.

In the spaces between the printing couples 10 the endless aprons or blankets 17 are arranged, each blanket extending substantially the entire vertical distance from the pass of one printing couple to the pass of the next lower printing couple. Each blanket is supported at its upper end by a roller 18 which is journaled in slide bearings 22 mounted 15 upon the bearing castings 15 for one of the impression rollers 13. The upper end of the frame 21 is loosely mounted on the ends of the shaft of the roller 18 and in the lower end of this frame a second roller 20 is mounted 20 around which the apron or blanket passes. A roller 19 is adjustably mounted upon the frame 21 and engages the inner side of one stretch of the blanket to properly tension the same.

25 The other stretch of the blanket 17 moves over the surface of a brass plate 21' carried by the frame 21.

At its lower end the frame 21 is adjustably supported against gravity movement by 30 means of the screws or bolts 50 which are threaded in rods 24 connecting the arms 23 which project upwardly from the bearing castings 15 of each impression roller. It will thus be readily understood that by adjusting the screws or bolts 50 the pressure 35 of the lower end of the apron or blanket 17 against the paper web may be properly regulated. The upper end of the blanket may also be similarly adjusted by means of the 40 screws 26' which have a loose or swivel connection to the slide bearings 22 for the upper blanket supporting roller 18.

To the rod 24 connecting each pair of bearing castings 15 a coil spring 26 is attached at one of its ends, the other end of the spring being connected to the inner end of a threaded rod 27 extending through the frame bar 28 of the press. A nut 29 is threaded upon the outer end of said rod 50 whereby the tension of the spring 26 may be properly adjusted as will be readily understood. The springs 26 act to normally withdraw the individual impression rollers 13 from peripheral contact with the respective printing cylinders 11.

In the operation of the press each of the blankets 17 is continuously driven at substantially the same speed as the speed of movement of the paper web. This driving 60 means for the blankets which I have not herein illustrated, may be similar to that shown in my application No. 362,030 above referred to. In another co-pending application for patent filed January 17th, 1922, 65 Serial No. 529,812, I have fully explained

how an induced electrostatic charge is produced in the operation of the blankets 17 by reason of their frictional rubbing contact with the surface of the metal plate 21' and I have also more fully described in the said 70 application the specific construction of the apron or blanket. It will, therefore, suffice for the purposes of the present disclosure to state that the induced electrostatic charges thus created between the spaced printing 75 couples result in subjecting substantially the entire area of the paper web extending between the couples to the attractive influence of the electrostatic charge so that the paper is drawn down and tightly held upon the 80 surface of the traveling blanket, which surface offers a very high frictional resistance to any tendency of the web to deviate from its line of movement between the passes of the printing couples. Thus an absolutely 85 precise and accurate registration of the web with the printing surfaces of the cylinders 11 is obtained and the improper superimposing of the impression from one cylinder upon that of another is obviated. It will be apparent that my invention, therefore, particularly lends itself to use in connection with a multi-color rotary gravure press, to which it has actually been applied and used with 90 great success.

Opposite the edge of each frame casting 15, a hand screw 30 is mounted in a part 31 of the press frame and at its inner end has a threaded connection with the nut 32. This nut is connected by means of toggle links 33 100 with the bearing castings 15 for the impression roller. Upon the transverse shaft 34 journaled in the side frames of the press, the cams 35 are fixed to engage with the respective toggles 33 and lock the same in extended position to thereby hold the impression roller 13 in engagement with the printing cylinder against the action of the springs 26. Upon a second transverse shaft 36 oppositely projecting arms 37 are fixed, the 110 upper edges of said arms engaging with the underside of the spaced pivot pins 38 when the toggle 33 is extended. Arms 39 and 40 fixed respectively to the shafts 34 and 36 are connected by a link 41, said link at one of 115 its ends having a slot 41' to permit of the shifting movement of the link upon the pin 40' fixed in the arm 40. Additional arms 42 are fixed upon one end of the shafts 34 120 exteriorly of the side frame 10 of the press, the said latter arms being pivoted to a common actuating bar or member 43. Any suitable means may be provided for imparting an operating movement to the member 43. When the parts are in the position seen in 125 Fig. 2 of the drawings it will be noted that all of the impression rollers are locked in their operative positions with relation to the printing cylinder by the engagement of the cams 35 with the toggle connections 33 and 130

since the apron or blanket frames 21 are mounted at their upper ends upon one pair of castings 15 and supported at their lower ends by the stop screws 25 of the next lower pair of castings, said blankets likewise will be maintained in their operative positions with relations to the web. When it is desired to relieve the web from contact by the impression rollers and blankets or aprons, the means is operated to actuate the connecting bar 43. This bar is moved in the direction indicated by the arrow or downwardly, and the cams 35 are first moved out of engagement with the toggles 33. The lower ends of the links 41 are simultaneously moved relative to the arms 40 and finally engage one of the arms 37 projecting from one side of the shaft 36, forcing the same downwardly while the other arm 37 exerts an upward pressure against one of the pins 38 and thus breaks the toggle connection, thereby permitting the springs 26 to contract, whereupon the several bearing castings 15 are rocked upon the supporting rods 16 so that the impression rollers are moved away from the printing cylinders. Owing to the manner of mounting the static charge producing blankets with their supporting frames as above described, said blankets are also moved simultaneously with the castings 15 and as a unit therewith out of their operative positions between the passes of the printing couples, so that the web is relieved from the influence of the electrostatic charges throughout the length of the web extending between the printing couples in one operation. The paper web can then be easily removed from the press and a new web threaded downwardly between the passes of the printing couples. The movement of the actuating bar 43 is now reversed so that the cams 35 are caused to exert a downward pressure upon the toggle connections 33, thereby spreading said connections and returning the impression rollers and the blankets to their former operative positions. While the throw-off mechanism above described in detail has given excellent results in practical operation nevertheless this specific throw-off mechanism is not necessarily essential to the purposes of the present invention, and it is not only possible, but in certain cases might be found desirable, to substitute various other mechanical variations for the throw-off mechanism herein disclosed. The present improvement is, therefore, to be understood as broadly comprehending a manually operable throw-off mechanism regardless of its detail characteristics which is in operative connection with the impression roller bearing castings or other parts associated with the impression rollers whereby the unitary shifting movement of the impression rollers and the web registering devices between the spaced

printing couples may be accomplished substantially in the same manner which I have hereinbefore described. In so far as I am aware, I believe it to be entirely new in the art to associate and arrange the impression 70 roller bearings and the registering devices in a web printing press so that they may be shifted or moved to operative or inoperative position as a single unit and by means of one and the same mechanical operation. 75 Accordingly, notwithstanding the more or less detail nature of my present disclosure, the invention is not to be otherwise limited, and my purpose to thus broadly define the improved combination in the appended 80 claims will at once become apparent.

I desire it to be further specifically understood that the web registering means might be considerably varied in its form and construction from that herein shown, and indeed it is not essential in the generic aspect of my present improvement that an electrostatic charge producing means shall be utilized for the purpose of effecting registration, although since I have found that the 90 utilization of such electrostatic charges gives the best results in practise, I have, therefore, claimed this feature broadly in combination with the impression roller bearings and the throw-off mechanism connected 95 therewith.

In view of the foregoing, it is to be understood that I reserve the privilege of resorting to all necessary mechanical modifications which may be required in order to satisfactorily meet peculiar conditions incident to the type of press to which the improvement is applied and as may fairly be considered to come within the spirit and scope of the invention as claimed. 105

I claim:

1. In combination with a printing press having a plurality of spaced printing units, each including an element having movably supported bearings, a web registering device arranged in each of the spaces between the spaced printing units, means supporting the web registering devices between and upon the movable bearings of the adjacent printing units for movement as a unit with 110 said bearings, and a manually operable throw-off mechanism connected to said bearings. 115

2. In combination with a printing press having a plurality of spaced printing units 120 each including a bodily movable element, web registering devices arranged in the spaces between the printing units, means supporting said web registering devices for movement as a unit with said bodily movable elements of the printing units, and a throw-off mechanism for simultaneously moving all of said elements and the registering devices into and out of effective relation with the web. 125

3. In combination with a printing press having spaced printing couples each including an impression roller having movable bearings, web registering devices arranged in the spaces between the printing couples, means for mounting said devices upon the impression roller bearings of adjacent couples for movement as a unit therewith, and a throw-off mechanism common to all of the printing couples and operatively connected with the impression roller bearings thereof to simultaneously move the impression rollers and the registering devices into or out of effective relation with the web.
4. In combination with a printing press having a plurality of spaced printing couples each including an impression roller and movable bearings therefor, web registering devices arranged in the spaces between the printing couples, means for mounting said registering devices upon the impression roller bearings of adjacent couples for adjustment relative to said bearings and for bodily movement as a unit therewith, and a throw-off mechanism common to all of said printing couples and operatively connected to the impression roller bearings to simultaneously move the impression rollers and the registering devices into and out of effective relation with the web.
5. In combination with a printing press having a plurality of spaced printing couples each including an impression roller and movable bearings therefor, web registering means arranged in the spaces between said printing couples, each of said means comprising an electrostatic charge inducing device, means for mounting said device upon the movable impression roller bearings of adjacent printing couples for adjustment relative to the web and for movement as a unit with said bearings, and a throw-off mechanism common to all of the printing couples and operatively connected to said bearings to simultaneously move all of the impression rollers and the web registering means into or out of effective relation with the web.
6. In combination with a printing press having a plurality of spaced printing couples each including an impression roller and movable bearings therefor, means supported between and upon the movable impression roller bearings of adjacent couples for subjecting the web extending between said couples to the influence of an induced electrostatic charge to maintain the web in registering relation with the printing sur-
- faces, and a throw-off mechanism common to all of said printing couples connected to the impression roller bearings to simultaneously move the impression rollers and the electrostatic charge inducing means into and out of effective relation with the web.
7. In combination with a printing press having a printing unit including complementary elements, means acting to normally withdraw one of said elements from operative relation to an opposed element, and manually controllable means including pivotally connected parts to retain said elements in operative relation against the action of said withdrawing means and a member coacting with one of said parts operating to lock said pivotally connected parts against relative pivotal movement.
8. In combination with a printing press having a printing unit including complementary elements, means acting to normally withdraw one of said elements from operative relation to the opposed element, means for adjusting said first named element when in operative position, including relatively movable parts, means coacting with one of said parts to lock said first named element in its adjusted position in operative relation to the opposed element, an element coacting with one of said relatively movable parts, and a common means for actuating said last named means and said element to thereby cause a relative movement of said parts and permit said first named means to withdraw said element from its operative position.
9. In combination with a printing press having a plurality of spaced printing couples each including a printing cylinder and an impression roller, means for withdrawing each of the impression rollers from operative relation with the associated printing cylinders, toggles for holding the impression rollers in operative position against the action of said withdrawing means, means for locking each toggle in an extended position, a braking means for each toggle, and a common manually operable means for first actuating the locking means to released position and then actuating said braking means to thereby permit of the simultaneous action of all of the withdrawing means to simultaneously move the impression rollers to an inoperative position.
- In testimony that I claim the foregoing as my invention, and I have signed my name hereunder.

CHARLES F. DAUSMANN.
